UNITED STATES PATENT OFFICE.

EDWIN A. CAVINESS, OF BATTLE CREEK, MICHIGAN.

HORN OR AMPLIFIER FOR PHONOGRAHS.

1,412,772.

Specification of Letters Patent. Patented Apr. 11, 1922.

Application filed November 22, 1919. Serial No. 339,898.

To all whom it may concern:

Be it known that I, EDWIN A. CAVINESS, a citizen of the United States, residing at the city of Battle Creek, county of Calhoun, 5 State of Michigan, have invented certain new and useful Improvements in Horns or Amplifiers for Phonographs, of which the following is a specification.

The invention relates to improvements in 10 horns or amplifiers for phonographs.

The main objects of this invention are to provide an improved horn or amplifier for phonographs which produces very clear tones, tones caused by sympathetic vibrations 15 being very largely eliminated.

Further objects, and objects relating to structural details, will definitely appear from the detailed description to follow.

I accomplish the objects of my invention 20 by the devices and means described in the following specification. The invention is clearly defined and pointed out in the claims.

A structure which is a preferred embodiment of my invention is clearly illustrated 25 in the accompanying drawing forming a part of this specification, in which.

Fig. I is a vertical section from front to rear of a phonograph cabinet having one of my improved horns installed therein, the 30 horn being shown in full lines.

Fig. II is a cross section through the bell portion of my improved horn on a line 2—2 of Fig. I.

Fig. III is a similar section through a 35 slightly modified embodiment of my invention, the top glass lining panel being omitted.

Fig. IV is an enlarged detail section on a line corresponding to line 4—4 of Fig. I, showing structural details.

40 Fig. V is an enlarged detail section on a line corresponding to line 5—5 of Fig. I, showing structural details.

Fig. VI is an enlarged cross section through the tube or neck of the horn on a 45 line corresponding to line 6—6 of Fig. I.

Fig. VII is an enlarged detail section on a line corresponding to line 7—7 of Fig. VI.

Referring to the drawing, 1 represents the 50 body of a cabinet phonograph. As the details of the cabinet and reproducing mechanism proper form no part of my present invention, they are not illustrated or described herein.

My improved horn or amplifier comprises a curved neck portion 2 and a flaring bell 55 portion 3. Both the neck and bell portions are, in the structure illustrated, rectangular in cross section. The walls of the neck portion are formed of multiply veneer, there being seven plies in the structure illustrated. 60 The veneer plies 4 are coated with a hard gum such as shellac represented at 5, and the coated surfaces are glued together as represented at 6 in Fig. VII. No attempt is made to show the thickness of the veneer 65 and the coating of the surfaces in relative proportions in this figure, although it is desirable to have the coating of shellac or similar gum of substantial thickness. This forms a very rigid neck portion of the instrument and one in which sympathetic sound vibrations are substantially eliminated. 70

The bell portion 2 comprises the outer walls 7 of wood glued together to form a 75 rigid joint between them, and the inner panels 8 and 9 of glass. These panels are substantially coextensive with the inner surfaces of the walls and are secured thereto by clips 10. Packing strips 11 are arranged 80 between the edges of the top and bottom walls 9 and the side walls 8. In Fig. III the top lining 8 is omitted.

My improved horn produces tones of very clear bell-like quality in which, as stated, 85 substantially all tones caused by sympathetic vibrations are eliminated.

I have illustrated and described my improvements in an embodiment which I find to be very practical and satisfactory. I have 90 not attempted to illustrate or describe various modifications which might be desirable to adapt my improvements to different styles of cabinet or instrument as I believe the disclosure made will enable those skilled in 95 the art to which my invention relates to embody or adapt the same as may be desired.

Having thus described my invention, what I claim as new and desire to secure by Letters Patent is:

1. A horn comprising a bell portion having outer rigidly united walls of wood, and linings therefor of glass panels substantially coextensive with the interior surfaces of 105 the walls and held against the same by clips

engaging the ends of said panels, there being packing strips between the adjacent portions of said panels.

2. A horn comprising a bell portion having outer rigidly united walls of wood, and linings therefor of glass panels substantially coextensive with the interior surfaces of the walls.

In witness whereof, I have hereunto set my hand and seal in the presence of two ¹⁰ witnesses.

EDWIN A. CAVINESS. [L.S.]
